one or more openings or recesses, as indicated at 20, so that, when the plug is turned, for example to the position shown in Fig. 4, the coil spring 15 depresses the plunger 13 so as to withdraw the outer end thereof from behind the abutment 14, and thus free the lock from the knob and permit ready axial withdrawal thereof.

The assembly of the lock with the knob may be the reverse of the disassembly just described, 10 that is, the plug is turned by means of the reset key to the position shown in Fig. 4 and the lock assembly then inserted axially after which the plug 7, together with the sleeve 16, is turned by means of the reset key and the inner end 17 of 15 the plunger 13 rides up on the inclined side of the recess 20 until the parts reach the relative rotative position illustrated in Fig. 2, when the reset key may be withdrawn and the pin 19 will then drop down to its normal position, and the 20 plunger 13 will likewise drop to its normal position shown in Figs. 1 and 2.

It will thus be seen that I have provided a relatively simple means for securing a lock in a case, such as a knob, and have provided relatively simple means for permitting release of said holding means and withdrawal of the lock from the case.

While the invention has been described in considerable detail and a preferred form illustrated, it is to be understood that various changes may be made in the mechanism and various embodiments of the invention made within the scope of the invention as defined in the appended claims.

I claim:

1. In a device of the character indicated, a knob having an opening, a cylinder lock to be received therein and comprising a cylinder and a key plug, tumbler mechanism for securing said knob and cylinder against axial separation, said tumbler mechanism having a plurality of shear lines and operable by means of a reset key to cause one shear line to permit rotation of said key plug, and means for automatically moving a part of said tumbler mechanism to release said cylinder lock for axial separation from said knob upon rotation of said key plug by said reset key.

2. In a device of the character indicated, a knob having an opening, a cylinder lock to be received therein and comprising a cylinder and key plug, said cylinder and knob having adjacent abutment means and a single member engageable with both said abutment means for holding said lock in said knob, a spring for normally urging said member out of engagement with one of said abutments to release said lock from said knob, dogging means cooperating with but movable relatively to said key plug and normally holding said member in locking position, and means operable by a reset key for withdrawing said dogging means and permitting said member to be withdrawn from one of said abutment means.

3. In a device of the character indicated, a knob having an opening, a cylinder lock to be received therein and comprising a cylinder and key plug, said cylinder and knob having abut-

ment means, a member engageable with said abutment means for holding said lock in said knob, said key plug having a recess for the reception of a part of said member to release said lock from said knob, dogging means for normally holding said member in locking position and permitting free rotation of said key plug by means of a passkey, said dogging means being operable by means of a reset key to release said member from said dogging means and permit said member to be withdrawn from one of said abutments.

4. In a device of the character indicated, a lock case having an opening, a cylinder lock to be received therein and comprising a cylinder and key plug, said key plug, a sleeve rotatably mounted on said key plug, said key plug, sleeve, cylinder and lock case having registering openings therein, a plunger normally positioned in the openings in said cylinder and lock case for holding said lock against axial withdrawal from said case, a part of said plunger being normally in said registering openings in said sleeve and cylinder, whereby said sleeve will be held against rotation on said cylinder and will serve to hold said plunger in locking position in said case, a spring for urging said plunger in unlocking direction, and a pin carried by said key plug, said pin being operable by means of a reset key to cause the same to lock said key plug and sleeve together and permit said sleeve to move from beneath said plunger, whereby said plunger may be withdrawn by said spring to release said lock from said case.

5. In a device of the character indicated, a lock case having an opening, a cylinder lock to be received therein and including a cylinder and key plug, said cylinder and case having abutment means, a plunger normally engaging said abutment means for holding said lock against axial withdrawal from said case, means for normally holding said plunger in locking position and permitting rotation of said key plug, and means operable by a reset key for removal of said holding means for said plunger, whereby the latter may be withdrawn from one of said abutments to permit withdrawal of said lock from said case.

6. In a device of the character indicated, a lock case having an opening, a cylinder lock to be received therein and comprising a cylinder and key plug, a sleeve member rotatably mounted on said key plug, said sleeve member, cylinder and lock case having registering openings, a plunger normally engaging said openings for holding said lock case, cylinder and sleeve against rotation while permitting free rotation of said key plug, said sleeve serving to hold said plunger in locking position, and means operable by a reset key for releasing said sleeve from said plunger and permitting rotation of said sleeve with said key plug, one of said parts having a recess for the reception of said plunger when said key plug and sleeve are rotated to a predetermined position whereby said plunger is withdrawn from one of said openings to permit withdrawal of said lock from said case.

NORMAN B. HURD.
